The ornamental design for a viewing stand, as shown and described.

DESCRIPTION

FIG. 1 is a top perspective view of an embodiment of the viewing stand in an assembled configuration;
 FIG. 2 is a bottom perspective view of the viewing stand of FIG. 1;
 FIG. 3 is a front elevational view of the viewing stand of FIG. 1;
 FIG. 4 is a rear elevational view of the viewing stand of FIG. 1;
 FIG. 5 is a left side elevational view of the viewing stand of FIG. 1;
 FIG. 6 is a right side elevational view of the viewing stand of FIG. 1;
 FIG. 7 is a top plan view of the viewing stand of FIG. 1;
 FIG. 8 is a bottom plan view of the viewing stand of FIG. 1;
 FIG. 9 is a top perspective view of the viewing stand of FIG. 1 in an assembled configuration;
 FIG. 10 is a bottom perspective view of the viewing stand of FIG. 9;
 FIG. 11 is a front elevational view of the viewing stand of FIG. 9;
 FIG. 12 is a rear elevational view of the viewing stand of FIG. 9;
 FIG. 13 is a left side elevational view of the viewing stand of FIG. 9;
 FIG. 14 is a right side elevational view of the viewing stand of FIG. 9;

FIG. 15 is a top plan view of the viewing stand of FIG. 9;
FIG. 16 is a bottom plan view of the viewing stand of FIG. 9;
FIG. 17 is a top perspective view of the viewing stand of FIG. 1 in a keyboard configuration;
FIG. 18 is a bottom perspective view of the viewing stand of FIG. 17;
FIG. 19 is a front elevational view of the viewing stand of FIG. 17;
FIG. 20 is a rear elevational view of the viewing stand of FIG. 17;
FIG. 21 is a left side elevational view of the viewing stand of FIG. 17;
FIG. 22 is a right side elevational view of the viewing stand of FIG. 17;
FIG. 23 is a top plan view of the viewing stand of FIG. 17;
FIG. 24 is a bottom plan view of the viewing stand of FIG. 17;
FIG. 25 is a top perspective view of the viewing stand of FIG. 1 in a folded configuration;

FIG. 26 is a bottom perspective view of the viewing stand of FIG. 25;
FIG. 27 is a front elevational view of the viewing stand of FIG. 25;
FIG. 28 is a rear elevational view of the viewing stand of FIG. 25;
FIG. 29 is a left side elevational view of the viewing stand of FIG. 25;
FIG. 30 is a right side elevational view of the viewing stand of FIG. 25;
FIG. 31 is a top plan view of the viewing stand of FIG. 25; and,
FIG. 32 is a bottom plan view of the viewing stand of FIG. 25. The broken lines shown on the drawings are included for the purpose of illustrating environment and form no part of the claimed design.
